UNITED STATES PATENT OFFICE.

HENRY CULL, OF CHICAGO, ILLINOIS.

MATERIAL-ELEVATOR.

SPECIFICATION forming part of Letters Patent No. 739,296, dated September 22, 1903.

(Application filed August 1, 1901. Renewed June 29, 1903. Serial No. 163,662. (No model.)

To all whom it may concern:

Be it known that I, HENRY CULL, a citizen of the United States, and a resident of Chicago, in the county of Cook and State of Illinois, have invented certain new and useful Improvements in Material-Elevators; and I do hereby declare that the following is a full, clear, and exact description thereof, reference being had to the accompanying drawings, and to the letters of reference marked thereon, which form a part of this specification.

This invention relates more particularly to an elevator designed for the use of builders and others in elevating brick, mortar, or like material in hods. Heretofore many elevators of the class described have been devised, some of which have embraced a chain belt on which a hod or hods may hang by means of a hook permanently secured on the hod. Most elevators of the class have been of considerable width, thereby necessitating a relatively large opening through the floors of a building where used. This is objectionable, inasmuch as it seriously interferes with the finishing of a building.

The object of this invention is to provide a cheap, simple, strong, and durable construction which requires but small space laterally or longitudinally of the joists and which so carries the hod containing the material as to avoid entirely the dropping of mortar, bricks, or other material therefrom.

The invention consists of the matters hereinafter described, and more fully pointed out and defined in the appended claims.

In the drawings, Figure 1 is a front elevation, partly broken, of a device embodying my invention. Fig. 2 is a side elevation. Fig. 3 is a fragmentary perspective view illustrating the construction of the cages and ways. Fig. 4 is a transverse section through the ways. Fig. 5 is a similar sectional view with parts omitted, showing a modified construction of the ways. Fig. 6 illustrates a modification of the cage guide-pulleys. Fig. 7 is a rear elevation of the top frame or head. Fig. 8 is a side elevation of the same. Fig. 9 is a top plan view. Figs. 10 and 11 are details of the winch.

As shown in said drawings, the elevator-ways are secured on uprights A, two in number, arranged parallel and, as shown, approxi-

mately twenty-eight inches apart from outside to outside, so that when the joists of a building are set sixteen inches between centers, as usual, one of the joists of the floor of the building may be moved over to an adjacent joist, and said uprights will fit closely in the space thus formed. 55

B B indicate the elevator cages or cars—as shown, two in number and movable along ways a a', secured on opposite sides of said uprights.

The uprights may be of any desired size and of any preferred construction. As shown, 65 however, the same are formed from sections or lengths of material of a desired size and adapted to be secured or spliced together in any desired manner in alinement and provided with a plurality of holes extending 70 therethrough and spaced a given distance apart and which register with corresponding holes in the opposite upright when the device is erected. On opposite edges of each of said uprights are provided metallic inwardly-directed flanges or ways a, which may be formed either of angle-iron rigidly secured to the upright, as shown in Fig. 4, or of plates or straps of metal a', secured on the opposite side of each upright by bolts which pass through and 80 through the same, as shown in Fig. 5. The holes extending through said uprights are, as shown, of two sizes, the larger alternating with the smaller. Through said smaller holes stay rods or bolts extend, on which may be 85 provided a sleeve a², the ends of which abut against the inner side of the uprights and act to hold the same rigidly in position when the nuts on the stay-rods are set up.

C indicates a top or head frame, comprising, as shown, the vertical members or straps of metal C' C², adapted to fit closely between the ways of each upright and which afford means for rigidly securing said frame to the uprights by bolting the same thereto through 95 said smaller apertures. Near the upper end of said straps C' and C² and rigidly secured to each is the transverse horizontal plate or bar C³. Adjacent to the upright C' and rigidly secured to the bar C³ is the cross beam 100 or bar of metal C⁴, at the outer ends of which are secured the brace members c c, the inner ends of which are bolted to the plate or bar C³, adjacent to the upright C'. Angle-iron ties C⁵

connect the uprights below the frame thus formed. Braces $c' c'$, rigidly secured at their lower ends on said angle-iron ties, are rigidly secured at their outer or upper ends to the 5 ends of the cross-beam C^4 . Diagonal upwardly-extending braces $c^3 c^4$, which are secured, respectively, on the uprights C' and C^2 , are connected at their upper ends with the plate or bar C^3 , near the middle thereof, as 10 shown in Fig. 7. On the triangular frame thus formed are journaled sheaves $D D'$, which are grooved to receive a cable or line and which are arranged obliquely to each other, with their like edges projecting beyond the 15 upright to which the strap C^2 is secured and with their planes converging in front of the same. Said sheaves may be journaled in any desired manner on said top frame or head, as shown. However, a boxing or bearing is 20 secured on each outer end of said cross-beam C^4 , and a shaft is journaled therein, the inner end of which is secured on a boxing or bearing bolted on the plate C^3 , as shown in Fig. 9. Journaled transversely in the uprights is 25 the winch E , comprising a shaft E' , which extends through two of the corresponding larger holes in said uprights a convenient distance above the floor from which the device is to be operated. Said shafts are provided 30 at each end with a collar which engages against the uprights and on its end, beneath the sheaves D and D' , with a grooved drum e , adapted to receive a plurality of turns of cable from said sheaves, and with a ratchet- 35 wheel e' . The ends of said shaft are adapted to be engaged by the cranks $e^2 e^3$, whereby the same is operated. A shaft E^2 extends through said uprights in the next adjacent larger apertures above those occupied by the 40 shaft E' and is provided at one end with a double pawl e^4 , adapted to engage the ratchet e' from either side, and at the other end with an operating-lever e^5 , whereby said pawl may be lifted by an operator on the opposite side 45 of the elevator therefrom.

The elevator-cages each comprise a frame forming a rigid back wall B , having pulleys or rollers journaled on the rear side thereof to engage the ways on one side of the uprights. 50 A bottom or floor portion B' is rigidly secured at the lower end of said back portion at a right angle therewith and adapted to support the hod or hods of materials. As shown, diagonal braces b are secured on said 55 back wall and near the outer margins of the floor portion. A bracket or step b' is secured to said bottom portion and to the back wall and extends upwardly at its outer end to a point above said floor portion and is provided 60 with a socket to receive the hod-handle, as indicated in Figs. 2 and 3. A corresponding socket is provided in the opposite outer corner of the floor or bottom portion, as shown at b^2 , so that each cage, as shown, is adapted 65 to carry two loaded hods, one of which is supported slightly above the other.

Near the top of the back wall are the out-

wardly-extending wings $B^2 B^3$, arranged one above the other a distance equal to the height of the hod-head and on each side of the middle of the back wall. Each of said wings is adapted to support one of said hods laterally, said hods each leaning against the wing on the opposite side of the center from the socket supporting the hod-handle. 70 The ends of the cable or operating-line F are secured, respectively, to said cages, and one or more turns of the middle part of said cable are passed around the drum e , so that rotation of the drum in one direction serves 80 to elevate the one cage and lower the other, while rotation in the opposite direction reverses the operation. Preferably said cable ends are secured on said cages in alignment with the centers of gravity of the cages, as 85 shown more particularly in Figs. 1 and 2. This may conveniently be done by passing the cable end downwardly on the outer side of the wings and securing the same on the cage-backs by taking one or more turns or 90 hitches about cleats $b^6 b^7$. (Shown in Fig. 1.) For the purpose of directing said line centrally above the wing B^2 an arm or projection b^8 (shown in Fig. 2) may be employed, on the inner side of which the line is passed 95 before being carried around the wing B^2 .

The operation is as follows: The device being mounted and adjusted as described, a hod may be supported in the socket at b^2 , so as to lean inwardly against the back and 100 against the wing B^3 . A second hod may be supported on the step or bracket b' and leaned inwardly against the back and against the wing B^2 , as shown in Figs. 1 and 2. The center of gravity of each of said hods now falls 105 a considerable distance within the line of support, thereby acting to hold the hod by gravity more firmly in position. The loaded cage may now be elevated by means of the winch to the desired position, the other cage being 110 lowered. Arrived at the desired elevation, the hods may be lifted from the cage and carried to the place where the material is needed. When the operation of building has reached a height which makes 115 it desirable to elevate the materials to a greater elevation, the top frame may be disconnected and an additional section of the uprights bolted in position at the top of the uprights theretofore used and the head-frame 120 secured at the top thereof, as before described, when the operation is continued as before.

Obviously many details of construction may be varied without departing from the principle of my invention.

I claim as my invention—

1. In a material-elevator, a cage adapted to support a plurality of hods in an upright position on the same side thereof and one higher than the other without attaching the hods 130 thereto.

2. The combination in an elevator-cage of inwardly-directed wings, a socketed support for a hod-handle secured on the cage in such

position that the hod when in position leans inwardly and centrally against the back of the cage and one of said wings.

3. A cage for a material-elevator comprising a rigid back wall, rollers thereon to engage the ways, inwardly-directed wings located on each side of the middle of the back wall and projecting inwardly one above the other and a socketed support carried by said back portion and adapted to receive the end of the hod-handle, the hods when in position leaning backwardly and laterally against said wings.

4. In a device of the class described, the combination with sectional, parallel ways, of a plurality of elevator-cages, comprising rigid backs and floors, outwardly-directed wings on the backs thereof arranged above the floors at different heights on either side of the center, means for attaching a cable in alinement with the center of gravity of said cage, an adjustable frame at the top of the ways, sheaves journaled obliquely on said frame in alinement with the center of gravity of one of said cages and cables connecting said sheaves with said cages.

5. In a material-elevator the combination with the cages and sectional parallel ways having transverse opposite apertures therethrough, of an adjustable frame removably carried at the top of said ways, shafts journaled obliquely with each other on said frame, sheaves journaled on said shafts, a winch and cables attached thereto passing over the sheaves and attached to the cages.

35 6. The combination with a plurality of ways arranged parallel with each other of oppositely-movable cages adapted to move on said ways, a winch journaled between the ways and adapted to receive the bight of a cable the ends of which are secured on the respective cages and sheaves located at the top of the elevator and journaled obliquely to each other, said sheaves converging on one side at a point above the drum of the winch and on the other side being approximately in alinement with the center of gravity of the cages.

7. In a device of the class described, a double elevator comprising in combination a plurality of pairs of ways arranged parallel, a cage adapted to move along each pair of ways, sheaves located at the top of the elevator and arranged obliquely with each other, the periphery of said sheaves on one side of the center being directed to a point above and in alinement with the center of gravity of each cage, cables attached to said cages

and passing over the sheaves, and an adjustable head-frame for said elevator on which said sheaves are journaled.

60

8. The combination in an elevator with oppositely-movable cages, of ways therefor comprising a plurality of removable sections each consisting of a strip of material shaped at each end complementally with the ends of like sections, flanges on each edge thereof projecting on one side of the same and adapted to be engaged by rollers or trucks respectively of the cages.

9. A top frame for an elevator comprising upright members with transverse members rigidly secured thereto, a cross-piece secured on one of the transverse members, sheaves journaled at each end of said cross-piece with the peripheries thereof on one side the center approximately in alinement with the sides of an operating-drum and with the peripheries on the other side of center approximately in alinement with the centers of gravity of the cages.

75

10. The combination with a plurality of parallel ways constructed of duplicate interchangeable sections joined end to end, cages movable between said ways, an operating-drum or winch removably journaled between the ways, a removable top frame secured on the uppermost of said way-sections, sheaves journaled on each side of said top frame with their peripheries on one side of the center in alinement with the sides of the winch and on the other side thereof extending over centers of gravity of said cages.

80

11. In a device of the class described the combination with parallel vertical ways, of a winch journaled thereon, cages with outwardly and forwardly extending wings, pulleys or rollers on the back of said cages adapted to engage with said ways, an adjustable frame at the top of said ways, a plurality of sheaves journaled thereon obliquely with the ways, the outer and inner peripheries of said sheaves extending over the winch and the center of gravity of the cages and a cable connected at its ends to said cages and passing over said sheaves and around the winch.

85

In testimony whereof I have hereunto subscribed my name in the presence of two subscribing witnesses.

HENRY CULL.
